UNITED STATES PATENT OFFICE.

EDWARD W. JOHNSON, OF CHICAGO, ILLINOIS.

MULTIPLE-NEEDLE HOLDER FOR ELECTROLYSIS.

991,208.

Specification of Letters Patent.

Patented May 2, 1911.

Application filed February 14, 1910. Serial No. 543,805.

To all whom it may concern:

Be it known that I, EDWARD W. JOHNSON, a citizen of the United States, residing at Chicago, county of Cook, and State of Illinois, have invented certain new and useful Improvements in Multiple-Needle Holders for Electrolysis, of which the following is a specification.

My invention relates to multiple needle holders for electrolysis and has particular reference to improvements in the multiple needle holder shown and described in Patent Number 864,968 granted to me September 3, 1907.

15 The object of my invention is to provide a multiple needle holder for electrolysis which shall have greater flexibility as a whole and in its separate arms than the one afore mentioned.

20 A further object of my invention is to provide a multiple needle holder having means for attaching the device to the person of the patient and equip the same with improved means for attaching it to the head, 25 and auxiliary means for securing the device to the arm or back of a chair.

Other objects will appear hereinafter.

The device comprises generally a suitable base or support and a plurality of jointed arms attached to said support and having a needle holder at the free end of each arm. The arms are each formed of three sections connected by universal joints. The joints are preferably of the ball and socket type and comprise a socket member arranged upon the ends of the first and last sections of the arms and a ball formed upon each end of the intermediate section. The socket comprises a pair of rings between which the ball is clamped and the rings are flared sufficiently to give considerable movement to the intermediate section. It is obvious that the nearer the intermediate section approaches to an alinement with the widest portion of the flared socket, the greater the movement the arm will have. In the afore mentioned patent I have illustrated the flare of the socket in alinement with the longitudinal axis of the first section of the arm, consequently when the first and intermediate sections are turned at right angles to each other or thereabout as is its usual position, the lateral movement of the intermediate portion is greatly limited.

55 A further and particular object of the present invention is to so arrange the joint

between the first and intermediate sections, as to give ample lateral movement to the intermediate section when in the usual operative position. I also find that greater flexibility of the lower or end section of the arm is required at times to properly position the needle, without increasing the length of the arms. 60

A further object of my invention is to 65 improve this portion of the device.

My invention will be more readily understood by reference to the accompanying drawings forming a part of this specification and in which,

Figure 1 is a plan view of a multiple needle holder embodying my invention, Fig. 2 is a side elevation of the device illustrating but two arms, Figs. 3 and 4 are details. Fig. 5 is a view similar to Fig. 2 illustrating but 70 one arm and embodying a modified form of the last section and the needle holder. Fig. 6 is a detail section of the modification shown in Fig. 5, Fig. 7 is a detail, illustrating one form of device for attaching the 75 needle holder to a chair, and Fig. 8 is a side elevation of a modified form thereof.

Referring to the drawings, 1 indicates the base or support of the device which is preferably stamped out of sheet metal and then 80 bent into the form shown in the drawings. As shown it comprises a plate portion, 2 a pair of forwardly extending arms, 3—3 and an upper vertical arm, 4. The plate, 2 is riveted or otherwise secured to a steel plate 85 5, as by the rivets, 5'. The upper portion of the plate 2 is slightly offset as at 2' leaving a narrow space or recess 2" between the offset portion and the plate, 5 for a purpose hereinafter described. Instead of forming the arm, 4 as an integral portion of the base, 1, I may form it separately and connect it to the plate, 5 as shown in Fig. 5. To the plate, 5 is secured a strap, 6 by means 90 of which the device may be secured to the 95 person of the patient.

6' indicates a pad preferably formed of insulating material.

To attach the device to the head, I provide a novel spring clamp detachably secured thereto. This comprises a curved steel spring member, 7, one end of which is detachably secured within the recess 2" and to the other end of which is secured a pad, 7'. The end of the spring, 7 which enters 105 the recess 2" is provided with a notch, 7" which engages with the upper rivet, 5'. To

secure the device to the head the pad 6' is placed against the forehead and the pad 7' against the back of the head, the spring, 7, passing over the top.

5 The arm, 4 is provided with a socket for an electrical plug, 8 and the end of the arms, 3, are connected by a bolt, 9 which constitutes the pivot for the needle supporting arms. The plug, 8 is insulated from the
10 arm, 4, and is provided with a main line wire, 11 and the separate insulated wires 12 leading to the several needles. The arms are each formed of a plurality of sections connected by universal joints and are preferably pivotally connected to the support, 1.
15 As shown in the drawings, each arm comprises three sections, a first section, 13 an intermediate section, 14 and an end clamping section, 15 which holds the needle. The
20 first section is preferably formed of sheet metal stamped and bent into the form shown and comprises the main or body portions, 13 and the end portion, 13' which is turned at right angles thereto. The socket member
25 hereinbefore mentioned is formed upon the end, 13' of the arm and is flared in alignment with said portion and hence, at right angles to the body portion of the arm. The socket comprises the rings, 19 and 19'
30 formed upon the end of the arms and a clamp member, 21 respectively, the latter of which is secured to the portion, 13' of the arm by a bolt 22. It is obvious that with this construction the central portion, 14 will
35 have maximum lateral movement when the portions 13 and 14 are at substantially right angles to each other, which is the position they assume when in use. The middle section, 14 of each arm comprises a tubular
40 member equipped with a ball at each end, of which the ball, 20, forming a part of the joint just described is one and 24 the other. These sections are preferably made telescopic as shown, and as particularly de-
45 scribed in the afore mentioned patent.

In order to better position the needle, at times, I provide a joint in the lower or end section, 15 and to this end construct the same as follows:—25—25 indicate a pair of plates each having a ring, 26 which rings are outwardly flared forming a socket for the ball, 24. The outer ends of the plates 25 are spaced apart by a washer, 27 arranged between them on a rivet or bolt, 28. Intermediate of the ends, the plates are connected by a bolt, 29 which clamps them on the washer, 27 and the ball, 24. Pivoted to the rivet, 28 are a pair of plates, 30 having their ends bent as at 31 to form a socket, for the needle holders, 32, upon which they are clamped by a bolt, 33 passing through said plates intermediate of their ends. By this arrangement the needle holder, 32 may be placed in the desired position while maintaining the flared socket rings, 26 in aline-

ment with the section, 14. It is obvious that perfect flexibility of the arms is secured in this manner.

Instead of jointing the lower section in the manner just described, the needle holder may be swiveled to the end of the section and in Figs. 5 and 6 I have illustrated an arm embodying this modification. In this form the lower section, 15 is formed of a pair of plates, 50—50, each plate having a ring, 51—51, 52—52 at each end, the former forming the socket for the ball, 24 of the intermediate section and the latter forming a socket for a ball, 53 formed on or secured to the needle holder. The plates 50—50 are held apart by the stud, 54 and are clamped upon the balls, 24 and 53 by the bolts, 55 and 56 respectively. The needle holder is secured in a clamp, 57 secured to the ball 53.

It is frequently advantageous to provide a support for the device instead of attaching it to the patient, and to this end I provide means for attaching it to the arm or back of a chair. In Fig. 7 I illustrate a device such as I find convenient for attaching the needle holder to the back of a chair when operating upon the face. This comprises a clamp 35 adapted to be secured to the back, 36 of a chair and a bracket 37 extending upwardly from said clamp and bent forwardly as at 38 to extend over the head of the patient, terminating in a depending portion, 39 having a plate, 40 secured thereto. Upon the plate, 40 are a pair of bolts, 41 which extend through holes 5" in the plate, 5. The bolts are equipped with butterfly nuts or thumb nuts, 42 for securing the device thereto.

To attach the device to an arm of a chair a similar clamp may be employed, the main difference being that the bracket, 37 is made much shorter, and the plate, 40 is secured to the upper end thereof in a horizontal position. In Fig. 8 I have illustrated a slightly modified form wherein the plate 40 is secured to the upper end of a threaded rod, 45 which passes through a hole, 46 in the arm, 47 of a chair. Upon the rod, 45 are a pair of thumb or butterfly nuts, 48—49 by which it is clamped to the arm. It is obvious that by means of the thumb nut the height of the device may be readily adjusted.

Having described my invention what I claim as new and desire to secure by Letters Patent is:

1. In a device of the class described, a multiple needle holder comprising a base and a plurality of needle holding arms connected thereto in combination with means for detachably connecting said needle holder to the arm or back of a chair said means comprising a clamp portion, a bracket extending therefrom, a plate on the end of said bracket and means for detachably se- 125 130

- curing the base of said needle holder to said plate, substantially as described.
2. In a multiple needle holder, a base and arm pivotally connected thereto, said arm comprising a section pivotally connected to said base an intermediate section pivotally connected to the first said section and a jointed needle holding section pivotally connected to the lower end of said intermediate section, substantially as described.
3. In a device of the class described, a suitable base in combination with an arm pivotally connected thereto, said arm being formed of three sections, the end section comprising a pair of plates rigidly spaced apart at one end and having a two part clamp formed
- at the other end for holding the end of the adjacent section between them, a bolt connecting said plates intermediate of their ends, a second pair of plates pivotally connected to the ends of the first said plate and having their ends formed into a socket to receive the needle holder and means for clamping said plates on the holder, substantially as described.
- 20 25

In testimony whereof I have signed my name to this specification in the presence of two subscribing witnesses.

EDWARD W. JOHNSON.
